UNITED STATES PATENT OFFICE.

CECIL J. DALE, OF HABANA, CUBA.

SIPHON-BOTTLE TOP.

Application filed November 3, 1925. Serial No. 66,591.

This invention relates to siphon bottles and has for its object the provision of a simple structure whereby the discharge from the bottle may be controlled. The invention seeks to provide a device for the stated purpose which will positively cut off all flow when it is closed and may be quickly and easily manipulated to permit discharge when desired. The invention is illustrated 10 in the accompanying drawing and will be hereinafter fully set forth.

The drawing is a vertical section of a bottle top embodying the invention.

The bottle, indicated at 1, may be of any 15 preferred size and form provided with an annular shoulder 2 adjacent its mouth. In carrying out the invention, I engage around the neck of the bottle below said shoulder and abutting the same a split collar 3 which 20 is externally threaded to be engaged by a cap 4 having an outlet spout 5 projecting from its upper end and in communication with its interior. Intermediate its ends, this cap 4 is constructed with an internal 25 annular shoulder 6 and between the said shoulder and the mouth of the bottle is a gasket 7 and a diaphragm 8 which will be firmly clamped to the bottle when the cap is turned home upon the collar 3. Leakage 30 will be thereby avoided. At the center of the diaphragm 8, an opening 9 is formed therethrough, encircled by an upstanding annular valve seat 9', and on the upper side of the diaphragm concentric with said 35 opening is a spider or valve cage 10 housing a ball valve 11. Threaded through the top of the cap is an operating screw 12 provided with a milled head 13, the lower end of the shank of the screw being concave, as shown 40 at 14, to bear upon the valve 11 and hold it seated upon the valve seat 9' in closing relation to the port or opening 9 when the screw is turned home. To permit discharge 45 from the bottle, the screw is rotated in the proper direction to ride outwardly through the cap and the pressure of the carbonated liquid within the bottle will then lift the valve from its seat so that the liquid may escape through the valve cage 10 and the 50 outlet spout 5. Depending from the diaphragm 8, concentric with the port 9, is a tube 15, preferably of glass, which has its upper end seated in a collar 8' and extends

to a point near the bottom of the bottle, and around the upper end of said tube is a short 55 outer tube 16 which also depends from the diaphragm, being preferably integral with the diaphragm. The outer tube 16 is provided at its lower end with an inwardly extending annular flange 16' which fits closely 60 about the tube 15 so as to prevent transverse movement of the latter.

To fill the bottle, it is inverted in a proper frame or support and the source of supply is connected through a hose or the like with 65 the spout 5. Then, if the screw 12 be turned to release the valve 11, the bottle will be charged through the port 9 in an obvious manner. It will be very readily seen from the foregoing description, taken 70 in connection with the accompanying drawing, that I have provided an exceedingly simple and efficient device whereby a bottle containing a carbonated beverage or any liquid under pressure will be securely sealed 75 when discharge of the liquid is not desired and may be quickly and easily opened when discharge is wanted.

Having thus described the invention, I 80 claim:

A closure for bottle necks comprising a cap having a head and an annular wall adapted to be removably secured about the bottle neck, an annular internal abutment shoulder being formed in the cap and adapted to be disposed over the bottle neck, an outlet spout above said shoulder, a rigid diaphragm in said cap to be gripped between said shoulder and the bottle neck, said diaphragm being formed with a port, 90 an annular valve seat extending upwardly about the port, a collar depending from said diaphragm about the port and adapted to receive the upper end of an outlet tube, a thimble depending from said diaphragm 95 about said collar and at its lower end provided with an inwardly projecting flange to fit snugly about the outlet tube in spaced relation to said collar and prevent transverse movement of the tube, a valve to seat upon said valve seat, and externally operated means to releasably retain said valve upon its seat in closing relation to said port.

In testimony whereof I affix my signature.

CECIL J. DALE.
